CLAIM

The ornamental design for a water bottle, as shown and described.

DESCRIPTION

FIG. 1 is a front perspective view of a water bottle in a filled state;

FIG. 2 is a front view thereof;

FIG. 3 is a rear view thereof;

FIG. 4 is a left side view of water bottle in a filled state thereof;

FIG. 5 is a right side view of water bottle in a filled state thereof;

FIG. 6 is a left side view of water bottle in an unfilled state thereof;

FIG. 7 is a right side view of water bottle in an unfilled state thereof;

FIG. 8 is a top view in an unfilled state thereof;

FIG. 9 is a top view in a filled state thereof; and,

FIG. 10 is a bottom view in a filled state thereof.

Any broken lines which may be shown in the views depict portions of the water bottle that form no part of the claimed design.
